Des. 233,499
Patented Nov. 5, 1974

233,499

RESTAURANT DINING TABLE

James T. Sakata, 653 20th Ave.,
San Francisco, Calif. 94121

Filed July 2, 1971, Ser. No. 159,163

Term of patent 14 years

Int. Cl. D6—03

U.S. Cl. D6—179

FIG_1

FIG_2

FIG_4

FIG_5

FIG_3

FIG. 1 is a perspective view of a restaurant dining table showing my design.

FIG. 2 is a plan view of the top of the restaurant dining table.

FIGS. 3 and 4 are side views of the restaurant dining table respectively from two orthogonal directions.

FIG. 5 is a bottom view of the restaurant dining table.

I claim:

The design for a restaurant dining table, as shown.
